UNITED STATES PATENT OFFICE.

WILLIAM HECKERT, OF YONKERS, ASSIGNOR TO THE KORTING GAS ENGINE COMPANY, (LIMITED,) OF NEW YORK, N. Y.

IGNITING DEVICE FOR GAS-ENGINES.

SPECIFICATION forming part of Letters Patent No. 425,879, dated April 15, 1890.

Application filed June 15, 1889. Renewed March 19, 1890. Serial No. 344,570. (No model.)

To all whom it may concern:

Be it known that I, WILLIAM HECKERT, a citizen of the United States, residing at Yonkers, in the county of Westchester and State of New York, have invented certain new and useful Improvements in Igniting Devices for Gas-Engines; and I do hereby declare the following to be a full, clear, and exact description of the invention, such as will enable others skilled in the art to which it appertains to make and use the same.

My invention consists in a certain improved form of igniting device for gas-engines, hereinafter to be described and claimed.

15 In the drawings, Figure 1 is a side view of a gas-engine, showing my ignitor applied thereto, the end of the engine-shaft and the gearing attached thereto being removed.

Fig. 2 is an edge view of the lever and cam-20 roller for operating the ignitor. Fig. 3 is a side view of the same with the cam shown in dotted lines and the igniting device shown in section. Fig. 4 is a longitudinal section and an end view of the hollow valve-plunger in 25 said ignitor. Fig. 5 is a longitudinal section and end view of the thimble; and Fig. 6 shows similar views of the barrel, all forming part of said ignitor. Fig. 7 is a detail view of a shield for the igniting-jet.

30 The engine to which I have shown my invention applied is of similar construction to that described in applications, Serial Nos. 314,458 and 314,459, filed on even date herewith, in which B is the main shaft, from which 35 suitably gearing E' and C' transmits motion to the cam-sleeve D', revolving on the stud C and carrying the cam D, all as shown in Fig. 1.

A is the engine-frame.

The lever E is mounted on the stud e' and 40 vibrated by means of the cam-roller e, resting against the cam D, and the spring F', which surrounds the rod F, and is confined between the flange of the engine-frame and the adjustable nut f. The evident effect of this 45 gearing is to give the ignitor its necessary quick motion once in every two revolutions of the engine at the moment when the charge is to be exploded.

The ignitor proper consists of the hollow 50 thimble K, which is screwed into the valve-casing V of the engine and is in communica-

cation with the passage leading to the engine-cylinder, through which the ingoing charge of gas and air is drawn. The flange K' renders the joint gas-tight between the valve-casing 55 V and the thimble K. On the thimble is placed the sliding barrel G, which has a cap G' and the perforations H. Into a notch g is inserted the end of the cam-lever E, which transmits motion to the barrel of the ignitor 60 at the proper moment. Within the thimble K is placed the hollow valve-plunger L, which has its seat L' and its bored-out portion O. This interior portion is permanently in communication with the interior of the valve-casing and the valve-passages by means of the fine perforation M in the end of the valve-plunger. When the valve-plunger is lifted from its seat, the larger holes N N are uncovered by that motion. The valve-plunger 70 has the wings P P to guide it and the cut-away portions p to enable the gas to flow around and get at the openings N.

In the cap G' there is inserted an adjustable plug I, which strikes against the end of 75 the hollow valve-plunger when the barrel G is moved, so as to close the end of the thimble K. On the end of this adjustable plug a projection X, of any suitable incandescent material—such as lava—is placed so that when 80 the end of the thimble is closed by the plug I this incandescent tip is introduced into the interior of the hollow valve-plunger L. An igniting-jet burns at the orifice S of the gas-pipe R, which is controlled by the valve r, 85 and the flame is protected by the shield Q. The supply of gas for the running of the engine is admitted through the inlet-pipe T.

The method of operation in my invention is the following: The igniting-jet from the 90 orifice S burns continuously, the flame passing through the perforations N through the barrel of the ignitor and keeping the tip X in a state of incandescence. During the compression period of the engine's cycle of operations a fine stream of gas and air will be forced through the perforation M into the interior O of the hollow valve-plunger, and will be ignited by the igniting-jet; but the perforation M is so fine that it is impossible for 95 the flame to be transmitted back through it, on the principle that flame is not transmitted 100

through fine apertures, as is well known from the operation of the Davies safety-lamp. At the proper moment the cam D reciprocates the barrel and the cap carrying the adjustable plug I as it closes the end of the thimble K and strikes and lifts the plunger L from its seat within said thimble. This opens the larger passage-ways, and whatever flame has been trapped in the interior O of the valve-plunger travels back through the valve-passages to the cylinder and ignites the charge. If, as is frequently the case, the amount of flame trapped is not sufficient to accomplish this, the incandescent tip X insures the ignition of the gas which pours into the interior of the valve-plunger when the latter is lifted off its seat in the manner described, and renders the ignition of the charge positive and uniform.

Having therefore described my invention, what I claim as new, and desire to protect by Letters Patent, is—

1. In an igniting device for gas-engines, the combination of the thimble whose interior is in communication with the engine-cylinder, the hollow valve-plunger seated in said thimble and provided with a fine perforation, by which the interior of the valve-plunger is kept permanently in communication with the engine-cylinder, and also provided with other large perforations, which are uncovered when the valve is lifted off its seat, a barrel which slides on the thimble and terminates in a cap, through which there are perforations for the passage of the igniting-jet, and an adjustable plug in the end of said cap, so arranged as to strike the end of the hollow valve-plunger and to lift it from its seat, together with means for reciprocating said barrel, substantially as described.

2. In an igniting device for gas-engines, the combination of the thimble whose interior is

in communication with the engine-cylinder, the hollow valve-plunger seated in said thimble and provided with a fine perforation, by which the interior of the valve-plunger is permanently kept in communication with the engine-cylinder, and also provided with other larger perforations, which are uncovered when the valve is lifted off its seat, a barrel which slides on the thimble and terminates in a cap, through which there are perforations for the passage of the igniting-jet, an adjustable plug in the end of said cap, so arranged as to strike the end of the hollow valve-plunger and to lift it from its seat, and a projection of suitable incandescent material, so placed as to be introduced into the interior of the hollow valve-plunger when the end of the thimble is closed by the cap on the barrel, together with means for reciprocating said barrel, substantially as described.

3. In an igniting device for gas-engines, the combination of the thimble whose interior is connected with the engine-cylinder, the hollow valve-plunger seated in said thimble and provided with a fine perforation, by which the interior of the valve-plunger is permanently connected with the engine-cylinder, and also provided with other larger perforations, which are uncovered when the valve is lifted off its seat, together with the tip of incandescent material, which is alternately introduced into the interior of said valve-plunger, thereby lifting it from its seat, and withdrawn and exposed to a constantly-burning jet of flame, substantially as described.

In testimony whereof I affix my signature in presence of two witnesses.

WILLIAM HECKERT.
